UNITED STATES PATENT OFFICE.

MORTON L. ADLER, OF NEW YORK, N. Y., ASSIGNOR TO THE BRUNSWICK-BALKE-COLLENDER COMPANY, OF CHICAGO, ILLINOIS, A CORPORATION OF DELAWARE.

CLOSET-SEAT HINGE.

1,194,393.

Specification of Letters Patent. Patented Aug. 15, 1916.

Application filed June 17, 1915. Serial No. 34,653.

To all whom it may concern:

Be it known that I, MORTON L. ADLER, a citizen of the United States, residing at New York, in the county of New York and State 5 of New York, have invented certain new and useful Improvements in Closet-Seat Hinges, of which the following is a specification.

This invention relates to hinges for water closet seats having novel means securing the 10 seat thereto.

Heretofore hinges have been secured to closet seats by means of screws passing through a plate forming a part of the hinge on the under side of a seat and into the body 15 of the seat. While this is a cheap and fairly satisfactory arrangement with wood seats, previously in common use, the introduction of molded hard rubber seats makes it desirable to provide a much stronger and better 20 hinge, presenting a neater appearance than previously known hinges.

It is the object of my invention to provide a hinge of strong construction and neat appearance, which may be easily applied to 25 and is particularly adapted for use with molded seats.

A further object of my invention is the provision of a hinge for closet seats, one member of which is adapted to be partially 30 embedded within the seat, whereby the connection therewith is materially strengthened and the life of the seat is prolonged.

Other objects and advantages of my invention will be apparent as it is better understood by reference to the following 35 specification when read in connection with the accompanying drawing in which—

Figure 1 is a plan view of a closet seat provided with my improved hinge; Fig. 2 is 40 a vertical section on the line 2—2 of Fig. 1; and Fig. 3 is a vertical section on the line 3—3 of Fig. 2.

Referring to the drawings, 1 indicates a 45 closet bowl provided with a rearwardly extending flange 2.

3 indicates a seat, which may be of any suitable conformation and which is preferably constructed of a core 4, comprising a plurality of layers of wood forming a laminated structure covered with a veneer 5 of 50 hard rubber vulcanized to the core 4. While the core 4 is described as a laminated wood construction it may obviously consist of other relatively inexpensive material such

as vulcanized rubber compound consisting 55 largely of reclaimed rubber, the invention in the present instance residing in the hinge and the means for securing it to the seat.

The hinge comprises the members 6 having threaded extensions 7, whereby the members 60 may be secured to the flange 2 in the usual manner. The members 6 are provided with spherical heads 8 having openings 9 therein in which the rod 10 is pivotally mounted. Pivotally mounted on the rod 10 65 are the forwardly extending arms 11, preferably formed integrally at their opposite ends with a plate 12 adapted to be embedded within a recess 14 in the lower face and at the rear of the core 4 and preferably secured 70 thereto by means of screws 13. It is to be understood that the plate 12 and the arms 11 are embedded within and secured to the core 4 previous to the application of the veneer 5, which is vulcanized to the core 4, 75 entirely sealing the hinge-fastening means. It will be seen, therefore, that, when the seat 3 has been completed, one of the hinge members is securely fastened in place and that the complementary hinge elements may 80 be readily secured thereto, the result being a seat and hinge of very strong construction which presents at the same time a neater appearance than any hinge heretofore offered to the public.

While I have shown and described the 85 invention as embodied in a closet seat having a laminated core covered with a veneer of hard rubber vulcanized to the core, I reserve the right to embody the invention in 90 seats of other construction, as for example laminated or solid wood seats, or seats constructed of a core of relatively inexpensive material with a veneer of hard rubber vulcanized thereto. Furthermore, while my 95 invention is shown in connection with a seat *per se* it is to be understood that it is equally applicable to the cover which forms a part of the seat in the broader sense of the word and that the word "seat" as used in the 100 accompanying claims is intended to have the broader meaning, so that the application of the invention is not limited to the specific disclosure of the drawings.

It will be apparent that various changes 105 may be made in the form, construction and arrangement of the parts without departing from the spirit and scope of the invention,

or sacrificing any of its material advantages, the form hereinbefore described being merely a preferred embodiment thereof.

I claim:

- 5 The combination of a water closet seat and a hinge therefor, said seat comprising a core of laminated wood having a recess in its lower face at the rear of the core and a veneer of hard vulcanized rubber covering
- 10 the core, a plate extending transversely of the seat at the rear thereof and embedded in said recess above the veneer at a distance

from the rear edge of the seat, means for securing said plate to the core, and arms integral with said plate, at the ends thereof, 15 and seated in said recess above the veneer and extending through said veneer at the rear of the seat to receive parts of said hinge.

MORTON L. ADLER.
